UNITED STATES PATENT OFFICE.

EDWARD J. O'BEIRNE, OF EVANSVILLE, INDIANA.

CONSTRUCTING TOWERS.

SPECIFICATION forming part of Letters Patent No. 279,422, dated June 12, 1883.

Application filed January 18, 1883. (No model.)

To all whom it may concern:

Be it known that I, EDWARD J. O'BEIRNE, a citizen of the United States, residing at Evansville, in the county of Vanderburg and 5 State of Indiana, have invented certain new and useful Improvements in Constructing Towers; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 Figure 1 of the drawings is a representation of a tower. Fig. 2 is a side view of a portion of the same. Fig. 3 is a cross-sectional view of one of the posts. Figs. 4 and 5 are side views of part of the post, and Fig. 6 is a plan 20 view of the tower.

This invention has relation to the construction of towers for the display of electric or other lights in harbors or in navigable streams where light-houses are commonly used; and it 25 consists in the construction and novel arrangement of tower-sections composed of posts, girts, and braces, made of wrought-iron, and of fittings and couplings of malleable iron, and connecting-bolts, as will be hereinafter more fully 30 described, and particularly pointed out in the claims appended.

The object of this invention is to construct 35 a strong, durable, and cheap tower for displaying electric or other lights where needed in the interests of navigation or for other purposes; and in order to accomplish the object I build the top section first, raise it to the required height, and then build the next section beneath it, and continue to build successive 40 sections, raising the structure until all of the sections have been completed and joined and rested on a suitable foundation prepared for the structure.

45 Referring to the accompanying drawings, *a* designates the foundations or supports for the tower. These may be constructed in any well-known manner. The tower is preferably constructed in triangular form; but it may be constructed rectangular in form, and is surmounted 50 with a suitable top for the lights and operator.

The posts *b* are in star or **X** form, commonly

termed "star-iron," and are of wrought-iron, as are also the girts *c* and braces *d*.

The couplings or sleeves *e* are of malleable iron, and are provided with sockets *f* for the 55 reception of the ends of the girts *c*, inclined sockets *g*, and the ends of the diagonal braces *i*. In securing the sleeves to the posts *b* in the first instance bolts *h* are employed to hold the sleeves *e* in place; but after the girts and diagonal 60 braces are in place they coact to hold the sleeves in place on the posts.

Heretofore tubing, or what is commonly termed "gas-pipe," has been used in structures 65 of this character; but a great objection to employing posts of this kind lies in the fact that where the greatest strength is required threads are cut, which so weaken the posts at these points as to endanger the structure.

One or more of the posts *b* may be provided 70 with steps *l*, consisting of angle-irons bolted to the posts in any suitable manner, about twelve inches apart, to enable the attendant to ascend and descend the tower when necessary. The diagonal braces may be crossed, as 75 shown in the drawings, and may extend from the girts to the posts, or from girt to girt, or post to post, as safety may require.

In constructing the tower I prefer to follow the plan hereinafter described, although others 80 may be adopted which will prove equally advantageous. At each post or corner I erect a twenty-two-foot derrick, with gearing and tackle attached, after which the first or top section is built upon the ground, then stood on end, 85 and four guy-ropes attached to the top of the tower. The lower tackle-blocks are then hooked to the lower corners or base of the tower, and the tower-section is raised sixteen feet by turning the crank of the derrick-gearing. The 90 second section from the top is then built beneath the first section, the tackle overhauled and attached to the base of this section, and the derrick again operated to raise the two sections, and section after section is thus added until 95 the structure is completed and rested on its foundation and secured in place. The guy-ropes, which are of the best manila, are fastened to posts sunk in the ground at a suitable distances from the tower, to correspond with 100 its height when finished, and are increased in size at the completion of every hundred feet of

the tower by four additional guys. These guys are all removed when tower is completed. Having thus fully described my invention, what I claim as new, and desire to secure by Letters Patent, is—

1. In a tower for electric and other lights, the combination, with the star-iron posts *b*, of the girts and braces, and the sleeves provided with the horizontal and inclined sockets secured in place by bolts passing through the sleeves and posts, substantially as specified.

2. In a tower for electric and other lights or for other purposes, the star-iron posts *b*, in combination with the socketed sleeves and their securing bolts, substantially as specified. In testimony whereof I affix my signature in presence of two witnesses.

EDWARD J. O'BEIRNE.
